(57) **CLAIM**

We claim the ornamental design for a shower faceplate, as shown and described.

DESCRIPTION

FIG. 1 is a front perspective view of a faceplate for a shower device, such as a showerhead or a hand shower.

FIG. 2 is a rear perspective view of the faceplate shown in FIG. 1.

FIG. 3 is a front view of the faceplate shown in FIG. 1.
FIG. 4 is a rear view of the faceplate shown in FIG. 1.
FIG. 5 is a right side view of the faceplate shown in FIG. 1, the left side view being substantially a mirror image thereof.
FIG. 6 is a top view of the faceplate shown in FIG. 1, the bottom view being substantially a mirror image thereof; and, FIG. 7 is a rear perspective cross-sectional view of the faceplate shown in FIG. 1 to illustrate contours of the faceplate.

One or more side and/or bottom views of a shower device are mirror images of another view and, therefore, have been omitted.

Any broken line showing of the environment is for illustrative purposes only and forms no part of the claimed design.
